DOG MECHANISM FOR YARN WINDING MACHINES

Anthony M. Bartak, Kingsport, Tenn., assignor to
Eastman Kodak Company, Rochester, N. Y., a
corporation of New Jersey

Application December 20, 1945, Serial No. 636,196

10 Claims. (Cl. 242—18)

1

The present invention relates to winding machines for winding packages of yarn, thread, cord, or other strand material, and more particularly to a dog mechanism for such a machine.

The present invention has, therefore, as its principal object the provision of a new and improved form of dog mechanism for yarn winding machines.

A further object of the invention is the provision of a dog mechanism for a coning machine in which the motion of the traverse back is not restrained in one direction of movement by a force which is necessary to enable the mechanism to lock when turning in the opposite direction.

And still another object of the invention is the provision of a dog mechanism of the class described which eliminates the braking action of the traverse back as it moves in a clockwise direction during the winding operation.

Yet another object of the invention is the provision of a dog mechanism which eliminates the back pressure of the button guide so as to insure straight cones without dips in the sides thereof.

Still another object of the invention is the provision of a dog mechanism which is simple in construction, relatively inexpensive to construct, highly effective in use, and of longer life than prior dog mechanisms.

To these and other ends, the invention resides in certain improvements and combination of parts, all as will be hereinafter more fully described, the novel features being pointed out in the claims at the end of the specification.

In the drawings:

Fig. 1 is a partial view of a yarn winding machine showing a form of dog mechanism used prior to the present invention;

Fig. 2 is a view taken substantially on line 2—2 of Fig. 1 showing the braking apparatus of the dog mechanism shown in Fig. 1;

Fig. 3 is a side view of a portion of a yarn winding machine, showing a dog mechanism constructed in accordance with the preferred embodiment of the present invention; and

Fig. 4 is a front view of a new form of dog mechanism illustrated in Fig. 3.

Similar reference numerals throughout the various views indicate the same parts.

The coning machine most commonly used for winding synthetic filament yarn onto cones consists of a rotating spindle upon which the paper cone turns. A reciprocating guide which moves the yarn back and forth along the surface of the cone, various guides, tension devices, stop mo-

2

tions, etc. A typical example of this type of machine is shown in Fig. 1. In this figure, the yarn 11 is wound onto a paper cone 12 which revolves in a clockwise direction. The yarn is guided onto the cone by the reciprocating button guide 13 which is connected by means of the traverse arm 14 to a cam, not shown, which revolves about the point 15. The traverse arm 14 is mounted in a slot in the traverse back 16 which is pivoted at the point 15 in such a manner that it may move back as the cone fills up, allowing the button guide to be continuously, but slightly, pressed against the surface of the cone. The yarn 11 is pulled from the bobbin 17 through the tension gate 18, through the slab catcher 19, underneath the stop lever 20 and to the button guide 13.

Figs. 1 and 2 show a sketch of the present form of dog mechanism which is of the shoe and segment type toggle mechanism. In these figures the rotation of the cam about the point 15 is counter-clockwise, tending to cause the guide 13 to be thrown against the cone of yarn with an impact as the traverse arm 14 changes direction at the end of the stroke. To prevent this from occurring, the dog mechanism now in use consists of a shoe 21 which rides in a segment 22. The spring 23 exerts a force against a lever 24 which is rigidly connected to the dog rod 25, thereby pressing the shoe 21 up into segment 22, thus tending to lock the traverse back 16 from moving in a counter-clockwise direction. This locking force, which is a force exerted on the traverse back 16 tending to rotate it counter-clockwise about the pivot 15, is made up of weights 26 acting through a system of levers, not shown, and the force exerted by the counter-clockwise rotation of the cam traversing the traverse arm back and forth along the side of the cam, all of which is well known to those in the art. This force tends to rotate the traverse back counter-clockwise about the point 15 and changes at the point where the traverse arm 14 changes direction. Any lost motion of the mechanism causes the traverse back 16 to bounce, causing dips in the sides of the yarn, the disadvantages of which are apparent to those in the art.

In order to build a good straight cone, it is desirable that the tension should gradually decrease as the cone builds up so that the final tension is about one-half the starting tension. Along with the tension, the back pressure exerted by the button guide on the cone must be such that it will tend to smooth out the surface making a straight sided cone.

The quality of a cone yarn is, also, dependent upon the hardness or density as determined by the use of a durometer. All cones which do not fall within a standard tolerance (60 to 80) are rejected. The density is a function of the tension applied at the tension gate 18, Fig. 1, and the amount of back pressure applied to the button guide against the cone of yarn 12. Any increase in back pressure will raise the density of the cone of yarn.

In Fig. 1, it will be seen that with the prior mechanisms, the spring 23, acting on the lever 24, exerts a braking action against the clockwise movement of the traverse back 16. This force will vary according to the length at which the spring 23 is compressed on installing and upon how well the shoe 21 fits in the segment 22. Therefore, this braking action must be taken into consideration when determining the total back pressure against the cone. Due to this force, a great difference in the back pressure acting on the individual spindles of the machine has been encountered. For example, with one machine out of 18 spindles measured, the variation of back pressure was from 10 ounces to 25 ounces. This 15-ounce variation represents a total of 11 points of density. This variation gives considerable trouble at the speeds at which the yarn is run so that normal cone density is around 75 to 80 durometers. Therefore, only a small increase in back pressure is allowed in order to hold the cones of yarn within the density limits required.

Another difficulty which has been encountered is the short life of present dog shoe which necessitates constant readjustment. The present dog mechanism does not, therefore, prevent defective cones. In addition, the present dog is now installed on the inside of the machine which makes it very unhandy to make adjustments.

It has been found that the quality of the cone yarn may be greatly improved by eliminating the braking action present in the dog mechanism now in use and described above. This has been accomplished by an entirely new dog mechanism which will be described in connection with Figs. 3 and 4 of the drawings. A steel plate 30 is mounted out from the front 31 of the machine by means of two cylindrical spacers 32 and 33 to bring the plate 30 in position below the yarn cone, as shown in Fig. 4. A connecting link 34 has the upper end rigidly connected to a rod 35 depending from and secured to the traverse back 16 to thus rigidly connect the latter to the link 34. The lower end 36 of the link 34 is bifurcated and is pivoted on a pin 37 carried by the plate 30. The upper surface of the plate is inclined, as shown at 38 in Fig. 3, and slidably supports a wedge-shaped member 39, the upper inclined surface 40 of which is adapted to engage the surface 41 formed at the base of bifurcated ends 36 to wedge the member 39 between the surfaces 38 and 41 for a purpose to be later described. The wedge member 39 may slide downwardly along the surface 38 due to its own weight, but it is preferred to move the wedge member 39 positively by means of a weight 42 connected to the wedge 39 by means of a cord 43 which passes over the lower edge 44 of the plate 30 to permit the weight to hang vertically, as shown in Fig. 3. The weight 41 thus tends to move the wedge member 39 downwardly and to the right along the inclined surface 38 of the plate 30 to retain the wedge in wedging relation between the surfaces 38 and 41, as is apparent.

In practice, the dog mechanism operates as follows: The yarn 11 is wound on the paper tube

12 which revolves in a clockwise direction by a suitable driving means, not shown. The yarn 11 is guided onto the cone by the reciprocating button guide 13 which is connected by means of a traverse arm 14 to a cam, not shown, which revolves about the center line of the pin 37. The traverse arm 14 is mounted in a slot, not shown, in the traverse back 16 which, with the link 34, is pivoted on the plate 30 for movement as a unit about the pin 37 in such a manner that as the yarn cone builds up during the winding operation, the traverse back 16 and link 34 move in a clockwise direction about the pin 37 leaving a small space between the upper surface 38 of the plate 30 and the surface 41 of the link 34. As this space increases, through the clockwise movement of the back 16 and the link 34, the weight 42 moves the wedge member 39 downwardly along the surface 38 of the plate 30 to bring the surface 40 of the wedge 39 into engagement with the surface 41 of the link 34 to wedge the member 39 between the surfaces 38 and 41, as is apparent, to prevent the traverse back 16 from bouncing backwards in a counter-clockwise direction, the advantages of which will be readily apparent to those in the art.

This dog mechanism has proved to be positive in its action and to be self-locking to prevent the counter-clockwise movement of the back 16 and the link 34 about the pivot pin 37. As the back 16 and link 34 are fixed together and move as a unit about the pin 37, these members constitute, in effect, a single unit so that the traverse back may be broadly considered as pivoted on the plate 30 and movable about the pin 37.

By the use of this new form of dog mechanism, the machine efficiency has been greatly increased and the yarn quality has been improved. However, the factor which is considered the most important is the elimination of the braking action and the traverse back as it moves in a clockwise direction. Thus the total back pressure exerted on the cone of yarn may be reduced considerably from that formerly obtained with prior dog mechanisms. It has been found that a minimum back pressure may now be obtained as low as 2 ounces with a variation of 1 ounce, whereas the minimum practical setting of back pressure on the present dog mechanism shown in Figs. 1 and 2 is about 14 ounces, the actual back pressure running from 10 to 25 ounces, or a variation of 15 ounces. As a result of this improvement, it is impossible to lower the density of the cone to fall within the established standard range. This improvement has also made it possible to practically eliminate certain winding defects, such as bulged cones due to too much back pressure, and soft rings and loops due to a variation in the back pressure while the cone is being wound.

The apparatus of the present invention thus provides a mechanism by which the motion of the traverse back is not restrained in one direction of movement by a force which is necessary to enable the mechanism to lock when turned in the opposite direction. While such a dog mechanism is shown in connection with a cone winding machine, it is adaptable to any mechanism or machine where unrestrained movement is required in one direction combined with a positive locking stop in the opposite direction. This new and improved dog mechanism also eliminates the braking action of the traverse back as it moves in a clockwise direction, and also removes the back pressure of the button guide so as to insure straight cones without dips in the sides thereof.

While one embodiment of the invention has been disclosed, it is to be understood that the inventive idea may be carried out in a number of ways. This application is, therefore, not to be limited to the precise details disclosed, but is intended to cover all variations and modifications thereof falling within the scope of the appended claims.

I claim:

1. In a yarn-winding machine, the combination with a machine frame, a traverse back carried by said frame, a traverse arm movably mounted on said back, a button guide carried by and movable with said arm for winding yarn onto a rotating cone, of a dog mechanism for said machine comprising a support fixed on said frame, means for mounting said back for pivotal movement on said support to permit said back to move freely in one direction as the cone builds up, and separate means independent of said back carried by and movable relative to said support and engaging said back to prevent the movement of the latter in the opposite direction.

2. In a yarn-winding machine, the combination with a machine frame, a traverse back carried by said frame, a traverse arm movably mounted on said back, a button guide carried by and movable with said arm for winding yarn onto a rotating cone, of a dog mechanism for said machine comprising an inclined fixed support on said frame, means for mounting said back for pivotal movement on said support to permit said back to move freely in one direction as the cone builds up, and a member slidably mounted on said support and movable in said one direction with said back to continually wedge between the latter and said support to prevent the movement of said back in the opposite direction.

3. In a yarn-winding machine, the combination with a traverse back, a traverse arm movably mounted on said back, a button guide carried by and movable with said arm for winding yarn onto a rotating cone, of a dog mechanism for said machine comprising an inclined fixed support, means for mounting said back for pivotal movement on said support to permit said back to move freely in one direction as the cone builds up, a member slidably mounted on said support for movement relative thereto to engage said back continuously as the latter moves in said one direction to prevent the movement of said back in the opposite direction during winding, and means for moving said member positively relative to said support to maintain it in constant engagement with said back.

4. In a yarn-winding machine, the combination with a machine frame, a traverse back carried by said frame, a traverse arm movably mounted on said back, a button guide carried by and movable with said arm for winding yarn onto a rotating cone, of a dog mechanism for said machine comprising a fixed support on said frame, means for mounting said back for pivotal movement on said support to permit said back to move freely in one direction as the cone builds up, and slideable blocking means carried by and movable relative to said support and wedging between said support and back to prevent the movement of the latter in the opposite direction during winding.

5. In a yarn-winding machine, the combination with a traverse back, a traverse arm movably mounted on said back, a button guide carried by and movable with said arm for winding yarn onto a rotating cone, of a dog mechanism for

said machine comprising a fixed support, means for mounting said back for pivotal movement on said support to permit said back to move freely in one direction as the cone builds up, and a wedge member slidably mounted on said support and movable relative thereto to wedge continuously between said support and said back to prevent the movement of the latter in the opposite direction during winding.

10 6. In a yarn-winding machine, the combination with a traverse back, a traverse arm movably mounted on said back, a button guide carried by and movable with said arm for winding yarn onto a rotating cone, of a dog mechanism for said machine comprising a fixed support, means for mounting said back for pivotal movement on said support to permit said back to move freely in one direction as the cone builds up, a wedge member slidably mounted on said support and adapted to move as a unit and in constant engagement with said back as the latter is moved in said one direction to wedge continuously between said support and back to prevent the movement of the latter in the opposite direction during winding, and means for continuously maintaining said member in engagement with said back.

15 7. In a yarn-winding machine, the combination with a traverse back, a traverse arm movably mounted on said back, a button guide carried by and movable with said arm for winding yarn onto a rotating cone, of a dog mechanism for said machine comprising a fixed support, means for mounting said back for pivotal movement on said support to permit said back to move freely in one direction as the cone builds up, a contact surface formed on said back, and a wedge member slidably mounted on said support and adapted to be maintained in constant engagement with said surface during the winding of said yarn to prevent the movement of said back in the opposite direction.

20 8. In a yarn-winding machine, the combination with a traverse back, a traverse arm movably mounted on said back, a button guide carried by and movable with said arm for winding yarn onto a rotating cone, of a dog mechanism for said machine comprising a fixed support, means for mounting said back for pivotal movement on said support to permit said back to move freely in one direction as the cone builds up, a contact surface formed on said back, a wedge shape member slidably mounted on said support and movable into engagement with said surface, and means for sliding said member along said support as said back is moved in said one direction to maintain said member in constant wedging relation between said surface and said support to prevent the movement of said back in the opposite direction during the winding of the yarn.

25 9. In a yarn-winding machine, the combination with a traverse back, a traverse arm movably mounted on said back, a button guide carried by and movable with said arm for winding yarn onto a rotating cone, of a dog mechanism for said machine comprising a fixed support, means for mounting said back for pivotal movement on said support to permit said back to move freely in one direction as the cone builds up, a surface on said back spaced from said support, a wedge member slidably mounted on said support and adapted to move therealong to wedge continuously between said support and said surface when said back is moved in said one direction to prevent reverse movement of said back during wind-

ing, and means for moving said member positively along said support to maintain said member in wedging relation between said support and said surface.

10. In a yarn-winding machine, the combination with a traverse back, a traverse arm movably mounted on said back, a button guide carried by and movable with said arm for winding yarn onto a rotating cone, of a dog mechanism for said machine comprising a fixed support, means for mounting said back for pivotal movement on said support to permit said back to move freely in one direction as the cone builds up, said support having an inclined top surface sloping downwardly in said one direction, a contact surface on said back spaced from said top surface, a wedge member carried by said top surface and adapted to move downwardly thereof to wedge between said surfaces to prevent movement of said back in the opposite direction during winding, and grav- 20

ity actuated means connected to said wedge member for moving said member downwardly along said top surface and into wedging relation with both of said surfaces.
